UNITED STATES PATENT OFFICE.

AUBREY R. HARRISON, OF GARY, INDIANA.

AUTOMATIC RAILWAY-CROSSING GATE.

Application filed November 6, 1924. Serial No. 748,204.

This invention relates to improvements in automatically operated railway crossing gates.

The primary object of this invention is the provision of an automatically operated railway crossing gate which may effectively control traffic at grade crossings, to permit highway traffic which is within the zone of the intersection to proceed to safety, and at the same time preventing advancing highway traffic from entering the zone of the intersection during an approach of a train or other vehicular traffic on the railway.

An important object of this invention is the provision of a gateway structure to be used on grade crossings, embodying a pair of swinging gates at each side of the tracks at the intersection, which may be so operated that the gate at the right side of the highway will first close to prevent highway traffic from entering the danger zone of the intersection, and the gate at the other or left side of the road closing a short time after the gate at the right side of the road has closed, thus permitting any traffic which may be trapped in the intersection to escape along the highway, off the track.

A further object of this invention is the provision of electrically operated means to automatically control railway crossing gates and the like, so that one gate may be closed in advance of the other.

Other objects and advantages of this invention will be apparent during the course of the following detailed description.

In the accompanying drawings, forming a part of this specification, and wherein similar reference characters designate corresponding parts throughout the several views,

Figure 1 is a diagrammatic view, showing schematically the circuits and apparatus used to control right and left crossing gates; the gates being shown in their elevated position, as they appear when no railway traffic is near the intersection at which the gates are disposed.

Figure 2 is a view showing diagrammatically the manner in which the improved automatic operating means controls the gate structure to first close a right hand gate while the left hand gate is still elevated.

Figure 3 is a diagrammatic view, showing the details in Figure 2, with a progres-

sive movement thereof from the position in which the details are illustrated in Figure 2, and showing both right and left crossing gates closed to obstruct vehicular traffic over a highway from advancing into the zone of danger of a grade crossing.

Figures 4, 5, and 6 are diagrammatic views illustrating a grade crossing formed by the intersection of a highway and a railroad track, showing the improved gate structure and the relative positioning thereof with respect to a vehicle traveling on the railway track during its approach toward the intersection.

In the drawings, wherein for the purpose of illustration is shown only a preferred embodiment of this invention, the letter A may generally designate the improved automatically operated gate mechanism, which may include the gates B and C at each side of the railway crossing or intersection, operated by a motor D, and including a clutch or gear shift E for selectively placing the power of the motor D for operation of the gates B or C in proper sequence. Circuit means and apparatus F is provided for operation by railway vehicle travel to control operation of the motor D and the clutch mechanism E.

As is diagrammatically illustrated in Figures 4, 5 and 6, it is preferred to provide right and left gates B and C respectively at each side of a crossing 10 which is formed by the intersection of the highway 11. The gates B and C are preferably of the pivotally mounted vertically swinging type, and the gate B at each side of the intersection is adapted to be positioned to close vehicular traffic at the right side of the highway 11, whereas each gate C is adapted to close the road or highway to vehicular traffic at the left side of the highway, looking in the direction of travel. These gates B and C, while they are shown pivotally carried at the central axis of the highway 11, may be individually mounted on the sides of the highway, in so far as the broad principle of this invention is concerned.

The motor D for each pair of gates B and C preferably includes a drive shaft 15, with which the clutch or gear shift mechanism E cooperates. This shift mechanism E preferably includes a sleeve 17 splined upon the shaft 15, and which sleeve 17 carries a gear

19 adapted to be selectively shifted into meshing relation with the gear 20 of the gate B, or the gear 21 of the gate C. Any approved means of driving the gates B and 5 C from the gears 20 and 21 may be provided, such as the provision of the intermeshing helical gears 22 and 23 for the gate B, the latter gear 23 of which is keyed with the gear 20; and gears 24 and 25 of the helical 10 gear type for gate C and the gear 21. It is readily obvious that the sleeve 17 rotates with the shaft 15, and by sliding the same along the shaft 15 the gear 19 of the clutch mechanism E may be selectively meshed with 15 the gears 20 or 21, to elevate and lower said gates, in accordance with the invention to be subsequently described. It is preferred that retaining hooks 28 and 29, preferably resilient, be provided, for respective engagement 20 with projections 30 and 31 formed on the splined sleeve 17, to hold the gear 19 in its desired meshing relation with either the gears 20 or 21, as the case may be, and as is illustrated in the various views of the 25 drawings.

An interlocking relay circuit 39 is provided in connection with the rails of the roadbed G, and the rails of the roadbed G adjacent the highway 11 are insulated to 30 provide the parallel rail sections 35 and 36 at one side of the highway intersection, and parallel rails 37 and 38 at the other side of the highway crossing; these rails 35 and 36 being insulated from other rail sections 35 of the railroad, and also from the sections 37 and 38, as is illustrated in the drawings. An interlocking relay structure of any approved type is preferably provided, including 35 an electro-magnet 40 connected in circuit with the rail sections 35 and 36. These rail sections 35 and 36 remote from the connection of the magnet 40 therewith having a battery 41 connected thereto for use in the circuit of the magnet 40, which normally energizes the magnet 40, although the magnet 40 will be short circuited when any vehicle, such as a train rolls upon the sections 35 and 36 between the magnet 40 and the battery 41. In similar manner the interlocking structure 39 includes an electro-magnet 43 in circuit with the rail sections 37 and 38, and including in this circuit is a battery 44 connected in the rails 37 and 38, in accordance with well known constructions. Armatures 45 and 46 are normally attracted by the electromagnets 40 and 43, and out of engaging relation with a contact 47, which is a part of a signal and battery circuit 48, so that the signal and battery circuit 48 is normally open, except when a train or other vehicle passes over the railway track to bridge either the sections 35 and 36 or the sections 37 and 38, and at 60 which time in accordance with the well known interlocking relay operation, the

armatures 45 or 46 will engage the contact 47 to close the circuit 48. In this circuit 48 is preferably provided a master control relay structure 50, to be subsequently described. A storage battery 51 of the proper voltage is also within the circuit 48, and any suitable signalling device may be placed in this circuit, such as an incandescent lamp 52; audible signal bell 53; or motor controlled semaphore 54. Upon closing of the 70 circuit 48 the devices 52, 53 and 54 will be operated to signal to traffic on the highway 75 the approach of a train along the track G.

The master control relay consists of a solenoid structure including a coil 55, and a core 56 movable in the coil. One end of the core 56 is connected with a pivoted switch arm 57, and this switch arm 57 is a conductor, and disposed in the circuit 48; at its pivoted end being connected by wire 59 to the wire of the coil 55, and at its swinging end operating over an arcuate contact 60 which is connected in the circuit 48. A dash pot 61, of any suitable type, is connected with the switch arm 57 to normally 80 urge the same away from the solenoid structure, and which is counter to the action of the solenoid when the latter is energized. The arm 57 is always in contact with the arcuate contact 60, and the circuit 48 is never broken at this switch mechanism. However, the switch arm 57 performs its function as a switch arm, in connection with contacts 63, 64, 65 and 66, which are adapted 85 to be bridged by the arm 57 to close the gap between said contacts 63 to 66 inclusive, and the contact 60, so that the energy from the battery 51 is utilized for operating circuits 67, 68, 69 and 70.

The circuits 69 and 70 leading off from the contacts 64 and 66 respectively are connected with the gate arms B and C. These gate arms respectively operate over segments 72 and 73 disposed concentric with the pivot action of said gates, to close the circuits 69 and 70 through said contacts 72 and 73. The contacts 72 and 73 are connected in conducting relation, and a conductor 75 leads from these contacts for connection to one terminal of the motor D. A wire or conductor 76 leads from the other terminal of the motor D, and is connected in the circuit 48 at the opposite side of the storage battery 51 from that side of the storage battery with which the contact 60 is connected.

The contacts 63 and 65 above mentioned are respectively connected to circuits 67 and 68 which lead to spaced contacts of a current reversing switch 82, which is also connected in a circuit 76. The circuits 67, 68 and 76 are adapted to control a mechanism 80 by means of which the gear 19 is moved to properly engage either the gear 20 or 21, as the case may be, and as will now be de- 125 130

scribed during the cycle of operation of the improved automatically operated mechanism.

Assuming a vehicle K to be approaching 5 the intersection 10, from the direction illustrated in Figure 4 of the drawings. As it first enters on the rail sections 35 and 36, the gates B and C at both sides of the intersection in the highway 11 are in their 10 normally elevated position, and traffic is of course passing over the intersection 10. As the vehicle K advances along the trackway, in the direction of the intersection, it will short circuit the interlocking relay circuit 15 in which the electromagnet 40 is positioned permitting the arm 45 to swing to engage contact 47 and close circuit 48 wherein the battery 51 is positioned. This closing of the circuit 48 will energize the solenoid coil 20 55 and draw the core 56 upwardly therein, moving the switch arm 57 along the contact 60 toward the contact 63. Also, this closing of the circuit 48 will give a preliminary warning to traffic in the vicinity of the 25 intersection 10, through any of the signals 52, 53, or 54. As the switch arm 57 engages the contact 63, current will flow from the battery 51 across the contacts 60 and 63, into the circuit 67, through the double pole 30 current reversing switch 82 to the solenoid coil 83, and into the line 76 direct to the battery 51, completing the circuit. The solenoid coil 83 will thus be energized, and will draw the core 85 thereinto from the position 35 illustrated in Figure 1 of the drawings. This core 85 at its outer end is connected to a rocker arm 86; said rocker arm being pivoted at 87 intermediate its ends. The rocker arm 86 has connected therewith a 40 link or rod 88 which is connected, as at 89, to the sliding shaft 17 splined upon the motor shaft 15, and the solenoid including the coil 83 and the core 85 will thus move the shaft 17 from the position illustrated in Figure 1, wherein the gear 19 meshes with the gear 21, to the position as illustrated in Figure 2, so that the gear 19 meshes with the gear 20 of the right hand gate B. At the end of the movement of the rocker arm 45 86, a movement will be imparted to a connecting rod 90 which connects one end of the rocker arm 86 with the switch 82, to shift the position of the switch 82 for the purpose of reversing a current through the 50 coil 83. This delayed action of the solenoid core 85 upon the double pole changing switch rod 90 is occasioned because of the provision of a slot 93, in the end of the rod 90, within which one end of the arm 86 operates.

Before the reverse current switch 82 has been changed, however, the switch arm 57 has passed upon the contact 64, and this closes the circuit 69, through the gate B; segment 72; conductor 75; motor D; and

line 76 back to the battery 51, setting the motor D in operation, and as the gear 19 engages the gear 20, the gate B at the right hand side of the road will be lowered, while the gate C is still vertically upstanding. As 70 the gate B approaches its downward or horizontal closed position, the same will ride off the contact 72, breaking the current through the circuit 69, and said gate B will move into engagement with a contact 95. This 75 contact 95 is in a line 96, wherein an electromagnet 97 is positioned, and the circuit 69 will again be placed in active condition, as the gate B engages the contact 95. The motor D will be cut out of the circuit 69, 80 however, and the electromagnet 97 will be energized to hold the gate B by attracting armature 98 which is disposed on the gate B.

From the position illustrated in Figure 2, the switch arm 57 of the master control relay structure 50 will next move to engage the contact 65, closing the circuit 68, and sending current through the solenoid coil 83 in reverse direction to that above mentioned. This energizing of the coil 83 will 85 tend to rock the arm 86 from the position illustrated in Figure 2 to the position illustrated in Figure 3, and to mesh the gear 19 with the gear 21. The switch arm 57 continues to ride thereacross to engage the segment or contact 66, closing the circuit 70 through the gate C; contact 73; conductor wire 75; motor D; line 76 and back to the battery 51. This will set the motor D in 90 operation, and lowering of the gate C will 100 commence. As the gate C approaches its horizontal relation it will move out of engagement with the contact 73 and the circuit through the motor D will be broken, stopping the motor. The gate C will, however, move into engagement with a contact 105 100, and energize an electromagnet 101 which is in circuit with the battery 51, causing said electromagnet to hold the gate C closed in the position illustrated in Figure 3 110 of the drawings. All of this time, during movement of the switch arm 57, it will engage both the contacts 64 and 66, so that the electromagnets 97 and 101 are both energized.

After the train has passed over the sections 35 or 36, or 37 and 38, according to the direction of travel, and has passed the intersection 10, the interlocking relay 39 will of course become active, to open the circuit 48, and permit the dash pot 61 to act on the switch arm 57 for bringing the latter back to open all of the circuits in the gate operating mechanism. The gates B and C will then swing to an open relation 115 incident to the provision of counter weights 110 and 11 provided thereon.

From the foregoing description of this invention it is apparent that a novel type of crossing gate has been provided, which 120 125 130

will effectively control traffic, without liability of danger. It has been a common occurrence that highway traffic has been caught between the lowering gates in an intersection, during an approach of the train, but with this crossing gate operating mechanism, such trapping of highway traffic will be impossible, since the right hand gates are first lowered to obstruct traffic in the highway against crossing the intersection, whereas the left hand gates remain open for a short period of time, to permit any traffic which may be in the intersection to clear prior to lowering of the left hand gates, for closing off the entire highway at both sides of the intersection.

Instead of depending only on the electromagnets 97 and 101, as shown, to hold the gates closed, said electromagnets may be made to operate pawls meshing with gears 20 and 21, or to operate brakes, to accomplish the same purpose.

The time interval between closing of gates B and C may be regulated by means of the timed dash pot on the master relay, and by properly proportioning the length of contacts 63, 64, 65 and 66.

Various changes in the shape, size, and arrangement of parts may be made to the form of invention herein shown and described, without departing from the spirit of this invention or the scope of the claims.

I claim:

1. In a railway signal circuit the combination with a track circuit including a relay, a second circuit adapted to be opened by said relay including a control relay mechanism, a plurality of stop signal circuits adapted to be controlled by said control relay mechanism, and means to operate one stop signal circuit in advance of the other.

2. In a gate mechanism for controlling highway traffic at the intersection of a highway and a railway line the combination of gates for controlling traffic on the highway at the right and left sides of the road, a circuit including a storage battery, relay mechanism in circuit with tracks of the said railway and normally holding said circuit open, said relay being adapted to be short circuited by vehicle travel over said tracks whereby to close said circuit, a switch in said circuit, solenoid means in said circuit for operating said switch, a motor, gear shift means for selectively connecting the motor with either of said gates, electrically operated means controlled by said switch for shifting said gears, and circuit means for

said motor including said switch and electromagnets for holding said gates closed until said relay is opened.

3. In combination an interlocking relay, a circuit in which the interlocking relay is interposed for regulating said circuit, a battery in said circuit, a master control relay in said circuit including a movable switch arm, a pair of crossing gates, a motor, gear shift means for connecting the motor with either of said gates, solenoid means for regulating said gear shift mechanism, reverse current switch means cooperatively regulating flow of current through said solenoid means, and circuit means including the switch arm of said master control relay for regulating operation of said motor and said gear shift solenoid.

4. In a device for controlling traffic at the intersection of a highway with a railroad, the combination of a circuit including a storage battery, railroad controlled relay means for normally holding said circuit open and for closing said circuit when vehicular traffic is passing over said railroad, a master control relay in said circuit, a pair of crossing gates, a motor, gear shift mechanism adapted to connect the motor for operation of said gates one at a time, circuit means for the motor including said storage battery and including said master control relay as a switch, switch means for said last mentioned circuit means for each of said crossing gates whereby to close off said motor when the crossing gates are closed, electromagnetic means for holding the crossing gates closed so long as vehicular traffic is passing over the railroad in the vicinity of the crossing, and electrically operated gear shifting mechanism including said master control relay as a switch for shifting the drive of the motor from one gate to the other when the first gate is closed.

5. In a grade crossing signal mechanism the combination of a pair of pivotally mounted gates positioned at opposite sides of a road and adapted to move across the road at the crossing so that one controls traffic at the right side of the road and the other controls traffic at the left side of the road, a motor, gear shift mechanism for selectively keying either of said gates for operation by the motor, and means operated by railway traffic on the tracks in the vicinity of the crossing for setting said motor in operation and operating the gear shift mechanism to first close one gate in advance of the other.

AUBREY R. HARRISON.
